Filed Aug. 19, 1968, Ser. No. 13,192

Term of patent 14 years

Int. Cl. D19—01

U.S. Cl. D59—14

The figure on the drawing is a face view of a sheet of note paper embodying my new design.

The essential features of the design reside in the portions shown in solid lines, a conventional female image being shown in broken lines at the upper left of the sheet.

I claim:

The ornamental design for a sheet of note paper, as shown and described.
